CONVERTIBLE CAMERA-GUN TOY

John W. Ryan, Bel Air, and Floyd Evan Schlau, Redondo Beach, Calif., assignors to Mattel, Inc., a corporation of California

Filed Jan. 28, 1966, Ser. No. 812

Term of patent 14 years

(Cl. D34—15)

Fig. 8

Fig. 1

FIG. 4

FIG. 2

FIG. 3

FIG. 5

FIG. 6

FIG. 7

FIG. 1 is a perspective view of a convertible camera-gun toy showing our new design in closed position when converted to a movie camera;

FIG. 2 is a side elevational view thereof;

FIG. 3 is an end elevational view taken from the left of FIG. 2;

FIG. 4 is a top plan view of FIG. 1;

FIG. 5 is an end elevational view taken from the right of FIG. 2;

FIG. 6 is a side elevational view of the side opposite that seen in FIG. 2;

FIG. 7 is a bottom view of FIG. 6;

FIG. 8 is a perspective view of the toy when converted to a gun by extension of the lens portion and housing to form a barrel;

FIG. 9 is a side elevational view of FIG. 8; and

FIG. 10 is a top plan view of FIG. 9.

We claim:

The ornamental design for a convertible camera-gun toy, as shown and described.
